US00D769710S

(12) **United States Design Patent** (10) Patent No.: **US D769,710 S**
(45) Date of Patent: **** Oct. 25, 2016**

(54) **BEVERAGE CARTRIDGE**

- (71) Applicant: **Keurig Green Mountain, Inc.**,
Waterbury, VT (US)
- (72) Inventors: **Steven Raphaelson**, Watertown, MA
(US); **Michael Sack**, North Reading,
MA (US); **Enrico Raffaele Cafaro**,
Beverly, MA (US); **Ralph K. Maider,
Jr.**, Milton, MA (US)
- (73) Assignee: **Keurig Green Mountain, Inc.**,
Waterbury, VT (US)
- (**) Term: **15 Years**
- (21) Appl. No.: **29/541,043**
- (22) Filed: **Sep. 30, 2015**

(57) **CLAIM**

The ornamental design for a beverage cartridge, as shown
and described.

DESCRIPTION

FIG. 1 is a top, front, left perspective view of a beverage
cartridge showing a first embodiment of our new design;
FIG. 2 is a bottom, front, right perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a top, front, left perspective view of a second
embodiment thereof;
FIG. 10 is a bottom, front, right perspective view of FIG. 9;
FIG. 11 is a front elevational view of FIG. 9;
FIG. 12 is a rear elevational view of FIG. 9;
FIG. 13 is a left side elevational view of FIG. 9;
FIG. 14 is a right side elevational view of FIG. 9;
FIG. 15 is a top plan view of FIG. 9; and,
FIG. 16 is a bottom plan view of FIG. 9.
The broken lines in the drawings depict unclaimed subject
matter only and form no part of the claimed design.

1 Claim, 8 Drawing Sheets
